UNITED STATES PATENT OFFICE.

GEORGE E. KEMPER, OF RICHMOND, INDIANA, ASSIGNOR, BY DIRECT AND MESNE ASSIGNMENTS, TO LOUCK & HILL CO., OF RICHMOND, INDIANA, A CORPORATION OF INDIANA.

FURNITURE-CLAMP.

1,280,758.

Specification of Letters Patent.

Patented Oct. 8, 1918.

Application filed December 27, 1916. Serial No. 139,194.

To all whom it may concern:

Be it known that I, GEORGE E. KEMPER, a citizen of the United States, residing in the city of Richmond, in the county of Wayne and State of Indiana, have invented a new and useful Furniture-Clamp, of which the following is a full, clear, and comprehensive specification, being such as will enable others to make and use the same with exactitude.

In the manufacture of furniture, such as cupboards, cabinets, dressers, wardrobes, chifforobes, chiffonniers, and other similar articles, it is imperative, in order to accomplish the best results and at the minimum cost, that the assembled parts be securely clamped together in one or in two directions, in order to form close fitting joints, and while the parts are thus clamped together, 20 the joints may be secured by nailing or pinning, or other means; also providing means whereby the article being manufactured will be automatically squared and spaced, and whereby the product will be absolutely true 25 and uniform.

Other objects and advantages of this invention will suggest themselves in the course of the following description.

One manner of carrying out my invention 30 in a practical way is shown in the accompanying drawings, in which—

Figure 1 is a top plan view of the entire device, showing the same in open position.

Fig. 2 is a side elevation of the complete 35 clamp.

Fig. 3 is a top plan view of the clamp, showing the same in closed or clamping position.

Fig. 4 is an end elevation of the complete 40 clamp.

Fig. 5 is a detail view, taken in sectional elevation.

Fig. 6 is a perspective view of any one of the several standards or clamping-jaws.

Fig. 7 is a perspective view of the web 45 portion of one of the standards, and Fig. 8 is a detail view showing particularly one of the hangers for one of the shafts.

Similar indices denote like parts through 50 out the several views.

In order that the construction, the operation, and the many advantages of my invention may be fully understood and appreciated I will now take up a detailed description thereof, and will describe the sev-

eral features as fully and as comprehensively as I may.

The frame-work of this invention comprises two sets of sills, one set being disposed across and resting on the other set. 60

The lower set of sills includes six members which are denoted by numerals 1, 2, 3, 4, 5, and 6, the same being arranged in three pairs, the members of each pair being spaced slightly apart. Also the pairs of 65 sills are spaced considerable distances apart.

The upper set of sills includes the six members denoted by the numerals 7, 8, 9, 10, 11 and 12, the same being arranged in three pairs, the members of each pair being spaced 70 a short distance each apart. Also each pair of sills are spaced some distance apart.

A plurality of sub-sills, as the sub-sills 50 and 51, are secured across by bolts *a* to the undersides of the sills 1, 2, 3, 4, 5 and 6, in 75 order to make the frame-work more rigid, and to provide a support therefor.

All of said sills are formed, preferably, of timber, and all of the intersecting points are secured together by a plurality of bolts *a*, as 80 shown in Figs. 1 and 3.

Numerals 13, 14 and 15 denote longitudinal plungers, which are in the nature of metal bars, which are square in cross section, and which rest across the members 1, 85 2, 3, 4, 5 and 6, and they are located each between respective pairs of longitudinal sills 7—8, 9—10, and 11—12.

In like manner the cross plungers 16, 17 and 18 are located between the respective 90 pairs of sills 1—2, 3—4 and 5—6, and they are also square in cross section..

Secured to and extending down from the underside of the forward end portions of the sills 1 and 6 are the hangers 19 and 20. 95

Numerical 21 denotes a relatively large shaft, which is round in cross section and it extends between the hangers 19 and 20.

Extending out longitudinally from the ends of the shaft 21 are the pivots 22 and 23, which are eccentric to the shaft 21 with which they are integral. One or more apertures 24 are formed through the shaft 21 in which may be inserted the pins 24', by which said shaft may be rotated by hand. The 100 pivots 22 and 23 are mounted in the apertures of the respective hangers 19 and 20.

Secured to the under faces of the forward 105 end portions of the plungers 16, 17 and 18 are the respective yokes 25, 26 and 27, each 110

having a vertical slot therein whose width is such as to permit the shaft 21 to fit therein, but the length of said slot is such as to permit the shaft to move up and down equal 5 to the eccentricity thereof.

Similar to the above is the cross shaft arrangement: Secured to and extending down from the under sides of the left-hand portion of the sills 7 and 12 are the hangers 10 28 and 29. Numeral 30 denotes a shaft, similar to the shaft 21, and it extends between the hangers 28 and 29. Extending out longitudinally from the ends of the shaft 30 are the pivots 31 and 32, which are eccentric of the shaft 30 with which they are integral. One or more apertures 33 are formed through the shaft 30 in which may be inserted the pins 33' by which said shaft may be rotated by hand. The pivots 31 and 20 32 are mounted rotatably in the apertures of the respective hangers 28 and 29.

Secured to the under faces of the left-hand portions of the plungers 13, 14 and 15 are the respective yokes 34, 35 and 36, 25 each having a vertical slot therein whose width is such as to permit the shaft 30 to fit therein, but the length of said slot is such as to permit the shaft to move up and down equal to the eccentricity thereof.

30 It is now apparent that the yokes are mounted slidably around the respective shafts and that turning the shafts will manifestly cause the plungers to move endwise, reciprocating between the members of 35 the respective pairs of sills.

In arranging the device for a certain size of product to be clamped care is taken to have the parts so adjusted that simultaneously with the parts being clamped reaching 40 the desired degree of tightness the eccentrics will reach their maximum clamping effect, that is to say they will be on "dead center" thereby, in addition to their frictional contact, they will remain in that position until the levers are moved in one direction or the other.

45 A plurality of standards are provided, but as they are all of substantially the same construction a description of one will answer for all. The base A and the face B are formed of a single length or strip of heavy sheet metal, the two parts being bent at right-angles to each other, the face B being of considerably greater length than that of the base A. Letter C denotes the web, which is simply a triangular plate fitting the inner angle of the parts A and B. Angle-irons D and E are secured along on the inner face of the member B, and on each side of the 50 web C; and likewise angle-irons F and G are secured along on the inner face of the member A on each side of the web C. The angle-irons D, and E are secured to the web C by rivets H, while the angle-irons F 60 and G are secured to the web C by the rivets 65

I. The angle-irons F and G are secured to the member A by rivets J, and the angle-irons D and E are secured to the member B by the rivets K.

By the above it is apparent that I form 70 a very strong standard capable of withstanding great strain.

Certain of the standards, formed as set forth, are secured on and extend up from the surfaces of the inner end portions of the 75 sills, that is from the ends of said sills nearest the shafts 21 and 30. Also removably secured on and extending up from the outer end portion of each of the plungers is one of said standards, the same being located 80 on the ends of the plungers farthest from the shafts 21 and 30.

It will now be understood that the device being open, as in Fig. 1, a frame work, such as the assembled material for the body of 85 an article of furniture, may be placed in position on the surfaces of the upper sills, and between the various standards. Then by operating the pins 24' and 33' the shafts 21 and 30 may be so turned that the standards carried by the plungers will be moved toward the standards carried by the sills, thereby clamping the parts of the assembled article of furniture in all directions whereby the various parts thereof may be permanently secured together by nails or screws 90 or otherwise as desired.

Other standards may be secured either to the sills, as indicated at *x* in Fig. 3, or to the plungers, as indicated at *z*, or both, 100 either for the purpose of spacing shelves or partitions or for adjusting the clamp for various sizes of furniture.

I desire that it be understood that various changes may be made in the several details 105 of construction from that herein shown and described, without departing from the spirit of my invention and without sacrificing any of the advantages thereof.

Having now fully shown and described 110 my invention, what I claim and desire to secure by Letters Patent of the United States, is—

A furniture clamp comprising the combination of a plurality of lower sills arranged 115 in pairs spaced apart, a plurality of upper sills spaced apart and arranged in pairs at right-angles to the lower sills and secured thereto, sub-sills extending across underneath the lower sills and secured thereto, 120 metal bars forming plungers located between the members of each pair of the upper sills and resting slidably on the lower sills, metal bars forming plungers located between the members of each pair of the lower sills 125 and resting slidably on the sub-sills, hangers extending down from each group of sills, shafts extending across between each pair of hangers, yokes extending down from the plungers, said shafts being pivoted in said 130
